The ornamental design for the wheel fender with connector for an animal leash, as shown and described.

DESCRIPTION

FIG. 1 is a perspective view of a wheel fender with connector for an animal leash showing my new design;

FIG. 2 is a front view of the wheel fender with connector for an animal leash;

FIG. 3 is a back view of the wheel fender with connector for an animal leash;

FIG. 4 is a left side view of the wheel fender with connector for an animal leash;

FIG. 5 is a top view of the wheel fender with connector for an animal leash;

FIG. 6 is a right side view of the wheel fender with connector for an animal leash; and,

FIG. 7 is a bottom view of the wheel fender with connector for an animal leash.

The broken lines shown are for illustrative purposes only and form no part of the claimed design.
